UNITED STATES PATENT OFFICE.

GEORGE R. KING, OF DALLAS, TEXAS.

ELECTRIC APPLIANCE FOR HORSES.

SPECIFICATION forming part of Letters Patent No. 516,740, dated March 20, 1894.

Application filed March 18, 1893. Serial No. 468,659. (No model.)

To all whom it may concern:

Be it known that I, GEORGE R. KING, residing at Dallas, in the county of Dallas and State of Texas, have invented a new and Improved Electrical Appliance, of which the following is a specification.

My invention relates to an electric appliance, adapted for use on stallions, to stop and cure the habit of masturbation, and such invention consists in the peculiar and novel combination of parts, hereinafter fully described in the specification, and particularly pointed out in the claims, reference being had to accompanying drawings in which—

15 Figure 1 is a perspective view of the appliance. Fig. 2 is a similar view thereof with the upper plate detached, to illustrate the electric generating devices, and Fig. 3 is a view illustrating the appliance as applied to the

20 animal.

Referring to the accompanying drawings, A indicates a suitably constructed box or receptacle, preferably of the shape shown, the side and end walls *a a'* of which are formed of hard rubber or some other non-conducting material.

B indicates the bottom plate of brass or other metal, which projects beyond the end walls *a'*, as at *b b*, and provided with slots *b' b'* as shown.

C indicates the electric generating devices which are held in the box A, and which may be of any well known construction, one terminal of which contacts with the lower plate 35 B, while the other contacts with the top or cover plate D. This plate consists of a leather strap having a sheet brass or other metal cover *d*, and such plate has a contact portion E of an absorbent material which is adapted to fit 40 under the belly of the animal when applied for use.

F indicates a strap which is secured at its ends *f*, to the extensions *d' d'* of the cover plate, passes down through the slots *b'* in the 45 ends *b* of the bottom plate, and passes under but out of contact with the bottom plate B. Upon the under face of this strap F, is secured a metal plate G, centrally of which is a button *g*, which projects up through the strap F as 50 shown. The box or shield is adjustably se-

cured upon the stallion in the manner most clearly shown in Fig. 3 of the drawings, by reference to which it will be observed that it is held transversely under the belly and supported on straps J, K, and L, secured to rings 55 I on the ends of the upper plate D. The front ends *j* and *k* of the straps J and K are adjustably secured to a breast strap M while the upper ends of the straps L are buckled to a crupper strap N.

When the parts are adjusted to the animal as shown, the lower plate and button *g* are held from contact with the lower plate B. When applied to the animal in the manner stated, should the stallion have amorous desires and get an erection, the penis will come in contact with the lower plate G, push it upward, and thereby cause its button *g* to contact with the plate B, which movement in turn closes the circuit, which produces an electrical 65 shock, and causes a reaction, which has the desired effect or result.

Having thus described my invention, what I claim, and desire to secure by Letters Patent, is—

1. An electric appliance for the purpose described, comprising a box or support, a bottom and top plate insulated from such support, the electric generating devices electrically connected with such top and bottom 75 plates, and a yielding contact plate held under the bottom plate adapted to be moved into contact with the bottom plate, all substantially as and for the purpose set forth.

2. In an appliance for the purposes stated, 85 the combination of the box A having insulated sides and ends, the metal bottom B, the top plate D having extensions *d' d'*, the electric generating devices held in the box and electrically connected with the top and bottom 90 plate, the strap F suspended under the bottom plate B, and connected to the extensions of the upper plate, and a contact plate G on the under side of strap F, having a contact *g* projected up through such strap, all substantially as and for the purpose described.

3. In an apparatus for the purpose described, the combination with the bar A, having insulated sides and ends, and the electric generating devices held therein, and connect- 100

ed with the top and bottom plates, said top plate projected and provided with securing rings at its ends, of the strap F secured to the plate D and projected under the plate B, such strap having a contact plate G on its under face formed with a contact *g* adapted to be moved into engagement with the bottom plate B, and the securing straps whereby the appli-

ance can be adjustably held on the animal, all substantially as and for the purposes set forth.

GEORGE R. KING.
